US0D1112391S

(12) **United States Design Patent** (10) **Patent No.:** **US D1,112,391 S**
(45) **Date of Patent:** **** Feb. 10, 2026**

(54) **DEBUBBLER COMPONENT**

(71) Applicant: **Lam Research Corporation**, Fremont, CA (US)

(72) Inventors: **James Isaac Fortner**, Newberg, OR (US); **Chad M. Hosack**, Newberg, OR (US); **Robert Rash**, West Linn, OR (US)

(73) Assignee: **Lam Research Corporation**, Fremont, CA (US)

(**) Term: **15 Years**

(21) Appl. No.: **29/993,340**

(22) Filed: **Mar. 13, 2025**

Related U.S. Application Data

(62) Division of application No. 29/807,018, filed on Sep. 8, 2021.

CLAIM

The ornamental design for a debubbler component, as shown and described.

DESCRIPTION

FIG. 1 is a top, rear, right perspective view of a debubbler component, showing our new design.

FIG. 2 is a bottom, rear, left perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.
